UNITED STATES PATENT OFFICE.

GEORGE HERBERT POWER, OF TULSA, OKLAHOMA.

SIGN SUPPORT.

1,408,636.

Specification of Letters Patent. Patented Mar. 7, 1922.

Application filed March 23, 1921. Serial No. 454,657.

To all whom it may concern:

Be it known that I, GEORGE H. POWER, a citizen of the United States, and a resident of Tulsa, in the county of Tulsa and State of Oklahoma, have invented certain new and useful Improvements in Sign Supports, of which the following is a specification.

My present invention relates generally to sign supports, and more particularly to a support for holding a sign in such manner that it may be effectively and advantageously displayed and will be capable of movement in such a manner as to attract the attention of those within view of the same.

More particularly my invention aims to provide a support permitting of attractive movement of a sign under the effect of air currents.

The primary object of my invention is the provision of a support for signs permitting of limited swinging movement, more especially oscillation of the sign with respect to the support and causing vertical shifting movement of the sign during its swinging movements or oscillations. In my improved arrangement it is contemplated that the sign itself shall constitute a vane against which air currents operate to oscillate the same and through the particular manner of its support, bring about vertical shifting movement.

In the accompanying drawing illustrating my present invention and forming a part of this specification,

Figure 1 is a perspective view showing the invention complete,

Figure 2 is a detail view of the upper end of the support, partly broken away and in section,

Figure 3 is a top plan view, and

Figure 4 is a partial side view illustrating a slight modification.

Referring now to these figures and particularly to Figures 1 to 3 inclusive my invention proposes a support for signs, as for instance signs in the nature of a rectangular panel 10, the support including an upright 11 mounted at its lower end as for instance in concrete and the like 12, and provided adjacent to its upper end with a transverse pin 13 fixed diametrically therethrough with externally projecting ends adapted to cooperate with the notched lower end 14 of a tubular upper extension 15 whose lower portion telescopes the upper end of the upright 11. Projecting from the upper and lower ends

of this tubular upper extension 15 are sign supporting arms 16 and 17, the latter projecting horizontally and the former inclining outwardly and downwardly as shown. 60 These arms are joined at their outer ends and the lower horizontal arm serves to support sign panel 10 as for instance by means of eye bolts 18.

The structure thus far described is present 65 in both forms of the invention shown, the upright 11^a and the upper extension tube 15^a with its supporting arms 16^a and 17^a, the latter supporting a sign panel 10^a by means of eye bolts 18^a, being the same as the corresponding parts previously described in Figure 1.

In the construction of Figure 1, however, the upper end of the upright 11 is closed as shown in Figure 2 and has an upstanding 75 eye bolt 19 with which the lower end of a spring 20 may be engaged. The upper end of this spring which extends upwardly within the tube 15 has connection with the lower eye 21 of an adjusting bolt 22 threaded vertically through the upper closed end of the tube 15 and provided with a lock nut 23 serving to secure the same in adjusted position. This spring operates to create downward tension upon the tube 15 and thus 80 maintain the projecting ends of the pin 13 within the innermost portions of the grooves or recesses of the lower end 14 of the tubular extension 15, it being observed that due to this structure oscillating movements of the 85 tubular extension 15 under the effect of air currents against the sign panel, will bring about vertical movements of the tube 15 under tension and control of the spring 20.

According to the construction of Figure 95 4 the corresponding movements of the tubular extension 15^a are controlled by a weight 24 in the upright 11^a at the lower end of a flexible connection 25 whose upper end is secured at 26 to the tubular extension 15^a, 100 the upper end of the upright 11^a being in this form of the invention open to permit of free passage of the weight supporting connection.

In either form of the invention it is 105 obvious that oscillating movements of the sign panel, bringing about as they do vertical shifting movements thereof under tension of the movement controlling connections, in one instance spring 20 and in the 110 other instance weight 24 will be attractive to the eye and in this way draw the attention

of those within view of the sign, and it is also obvious that these movements are provided for and take place without necessitating manual control or attention beyond mere regulation or adjustment from time to time.

It is also obvious that due to the above facts the sign will be strong and durable in use and is economical both in first cost and upkeep.

10. It will further be noted that while the sign board may be mounted to normally stand at right angles to the line of travel at a roadway or street side, it is also adapted to swing around to an angle sufficient to protect both support and sign board from being being blown down or otherwise injured in high winds. In fact the swinging movement of the sign board is unlimited in this respect, complete revolution being allowed.

15. I claim:

1. A sign comprising a sign panel, a supporting upright, a tubular oscillatory extension telescoping the upper end of the upright and having recesses in its lower end provided with inclined walls, outstanding supporting arms carried by said tubular extension and to which the sign panel is connected whereby the latter may swing horizontally with the oscillations of said extension, a pin diametrically through the upright having its ends disposed in the recess of the

35. said tubular extension to engage the inclined walls and force vertical shifting of said extension during oscillation, and means connected at the upper end thereof to the tubular extension and exerting a downward pull on the same to yieldingly resist oscillating and vertical shifting movements of the tubular extension and the sign panel with respect to the upright.

40. 2. A sign comprising a sign panel, a supporting upright, a tubular oscillatory extension telescoping the upper end of the upright and having recesses in its lower end provided with inclined walls, outstanding supporting 45. arms carried by said tubular extension and to which the sign panel is connected whereby the latter may swing horizontally with the oscillations of said extension, a pin diametrically through the upright having its ends 50 disposed in the recesses of the said tubular extension to engage the inclined walls and force vertical shifting of said extension during oscillation, a spring within the tubular extension connected at its lower end to the upright and adjustable means at the upper end of the extension to which the upper end of the spring is connected, whereby to adjustably tension oscillating and vertical shifting movements of the tubular extension with respect to the upright.

55. GEORGE HERBERT POWER.
